UNITED STATES PATENT OFFICE.

AUGUSTUS D. WILLHAUCK, OF CAMBRIDGE, MASSACHUSETTS, ASSIGNOR TO UNITED SHOE MACHINERY CORPORATION, OF PATERSON, NEW JERSEY, A CORPORATION OF NEW JERSEY.

MACHINE FOR PERFORMING FINISHING OPERATIONS UPON BOOT OR SHOE PARTS.

Application filed January 21, 1926, Serial No. 82,698, and in Great Britain December 17, 1925.

This invention relates to machines for performing finishing operations upon boot or shoe parts and is herein illustrated as embodied in an upper seam pressing or rubbing machine of the type described in Letters Patent of the United States No. 1,701,845 granted February 12, 1929, in the name of F. M. Furber.

In the machine disclosed in the patent referred to a seam flattening hammer, moving through an orbital path, is arranged to deliver a rapid succession of wiping blows to a seam, and a seam opening tool, located in advance of the hammer and arranged to partake of its orbital movement, is repeatedly depressed between the margins of the seam and functions to open the seam by an intermittent clawing or scratching action adapted to prevent jamming of the work.

One object of the present invention is to provide an improved machine for performing finishing operations upon boot and shoe parts, which will be adapted to perform seam-pressing operations, and by which the performance of such operations may be still further facilitated by insuring that the seam will be so prepared for the operation of the pressing or flattening means that the pressed seam will be uniformly smooth and even throughout its length.

To the accomplishment of this object one feature of the invention consists in the combination, in a machine of the class described, of a finishing tool movable back and forth along the surface of the work, and a preparing tool slidably supported upon the finishing tool and held in continuous engagement with the work but mounted to yield in response to irregularities and variations in the work without moving the finishing tool. In the machine herein illustrated the finishing tool consists of a member or hammer for pressing or flattening a seam, such as the back seam of a shoe upper, and the preparing tool is in the nature of a plow arranged to open the seam and turn the margins thereof over against the body of the work before the seam is acted upon by the hammer. While being operated upon the work is supported upon and fed over the periphery of a driven feed roll. The hammer, in addition to moving toward and from the work, moves also in a

direction to co-operate with the feed roll in feeding the work while the plow is mounted upon the hammer for movement with the hammer in the direction of feed of the work but the plow is arranged to be independent of the movement of the hammer toward and from the work. The plow is acted upon by a light spring which urges it toward a fixed stop arranged to limit the approach of the plow toward the work supporting roll. This spring exerts only a light pressure upon the plow but the pressure is sufficient to prevent the plow from partaking of the movement of the hammer toward and from the work and to maintain the plow continuously in operative engagement with the work. The plow is permitted, however, to yield readily as may be required to accommodate variations in the thickness of the work. As shown, the plow is provided with a central wedge-shaped rib for entering readily between the margins of a closed seam, and a seam engaging surface is formed at each side of the rib, each surface being curved in two directions transverse to each other and arranged to extend both lengthwise and crosswise of a seam which is being operated upon so that the seam margins are separated and turned over toward the face of the work by gradual turning or rolling movements progressing simultaneously outward and downward. Inasmuch as the plow is shaped as just described and is arranged to remain continuously within the seam the seam will be opened smoothly and uniformly throughout its length.

In accordance with a further feature of the present invention, the transverse curvature of the seam engaging faces of the plow is made such that the outer edge portions of these faces at the rear of the plow project downwardly substantially below the highest portions in the rear edges of these faces. In operation these projecting edge portions of the plow direct the outer edges of the seam margins downwardly toward or against the face of the work, thus rolling over the margins and causing them to bulge upwardly between their outer edges and the line of stitching. When seam margins which have been thus prepared are acted upon by the pressing member the latter functions most effectively to flatten the seam and to insure permanence in the set of the seam.

The invention will be best understood from the following description of the preferred embodiment thereof illustrated in the accompanying drawings, in which:-

5 Fig. 1 is a side elevational view, partly broken away, of a portion of the improved seam rubbing machine;

10 Fig. 2 is a view partially in side elevation and partially in section on the line II—II of Fig. 1, showing the plow and the work support and a piece of work being operated upon;

15 Fig. 3 is a perspective view of the seam opening plow; and

20 Fig. 4 is a perspective view of the plow, together with portions of the pressing member, the work support, and the seam guiding fingers, showing these parts in operation upon a piece of work.

25 As stated above, the illustrated machine is of the type disclosed in Letters Patent No. 1,701,845, before referred to, and reference may be had thereto for a detailed description of the construction and operation of parts not herein fully disclosed.

30 In the illustrated machine, a work-supporting feed roll, indicated at 6, is driven, in the direction of the arrow in Fig. 1, from a main shaft 7 through driving connections comprising a bevel gear 8 fixed to the feed roll 6 and a bevel pinion 9 meshing with the bevel gear 8. The machine also comprises a seam opening plow 12 adapted for separating and turning back the margins of a seam in a piece of work, such as shown at W in Figs. 2 and 4, to prepare 35 the seam for pressing and flattening, a pair of fingers 10 for engaging the outer surfaces of the margins of the seam before it is opened and guiding the seam to the plow, and a seam pressing member or hammer 14, which operates to press and flatten the seam progressively 40 after it has been prepared by the plow.

45 The hammer 14 is pivotally mounted between the arms of a yoke 16 arranged to rock about a rod 18 and the hammer is moved through an orbital path by means of a continuously rotating eccentric 20 on the main shaft 7 to enable the hammer to impart intermittent ironing blows to the work which is both flattened and fed over the roll thereby. The 50 work engaging portion of the hammer is shaped to conform to the slight bulge or convex curvature of the periphery of the feed roll crosswise of the direction of feed and the arrangement is such that the foremost edge portion only of the hammer engages the work and exerts a biting as well as a pressing action upon the seam. The hammer 14 is heated by an electric unit 22 mounted within a stationary member 24 which is slotted as indicated at 55 26 to embrace the work engaging portion of the hammer 14 so that heat may be readily transmitted from the member 24 to the hammer.

60 The seam opening plow 12 is mounted upon the seam pressing hammer 14 and it is guided

for up-and-down sliding movements relatively to the hammer by means of a rod 28 which extends through the plow and is secured at its opposite ends to the hammer, and the plow is urged downwardly by the pressure of a light 70 spring 30 which encircles the rod 28 between the plow and a shouldered portion 32 of the hammer.

As herein illustrated, the plow 12 and the hammer 14 are relatively so arranged that while the plow partakes of the back-and-forth 75 movements of the hammer it does not partake of the up-and-down movements thereof which force the plow against the seam through the spring 30 which maintains the plow continuously in operative position within the seam. 80

In order that the sprng 30 shall be effective for the purpose stated, either the hammer 14 or the plow 12 is cut away to provide space 34 between the vertically overlapping portions of the plow and the hammer, and the plow is 85 provided with stop lugs 36 which project from its opposite sides and are normally held by the light pressure of the spring 30 in engagement with the upper edge surfaces of the slotted extremity of the heated member 24, all as clearly 90 shown in Fig. 1. The stop lugs 36 function to determine the normal vertical position of the plow and to prevent it from coming into contact with the feed roll 6. By providing the space 34 between the hammer and the plow the 95 hammer is enabled to rise and fall without producing a corresponding rising and falling movement of the plow and thus, although the plow is constrained to move back and forth in unison with the hammer, it will not be lifted 100 out of the seam when the hammer rises but will remain in the seam at all times.

105 The plow 12 is formed with a central depending rib or fin 40 arranged to enter between the sides or margins of a closed seam. The rib 40 is highest at its front end to accommodate the widest seam which is to be operated upon and the front end of the plow is defined by a sharp vertical edge 42 which facilitates the entrance of the plow between the margins of the seam as the work is fed past the reciprocating plow. The rib 40 also has a well-defined and fairly sharp lower edge 44 which extends throughout the length of the plow and is arranged as best shown in 110 Fig. 1 so as substantially to conform to the curvature of the work supporting feed roll. The stop lugs 36 position the plow with the rib 40 spaced away from the periphery of the feed roll 6 so that the rib of the plow will continuously be located between the seam margins in position to ride along the line of 115 stitches making up the seam practically without exerting any pressure upon the stitches. To enable the plow to perform its seam opening function, the opposite sides of the rib 40 taper both upwardly from the lower edge of the rib and rearwardly from the forward or entering end of the rib. The tapering 120 sides of the rib terminate in curved surfaces 125 130

which merge with the lower curved surface of the body portion of the plow at either side of the rib, thus providing at each side of the rib a seam engaging surface which is curved about two axes disposed substantially at right angles to each other, or, in other words, each surface curves both lengthwise and crosswise with respect to a seam which is being operated upon by the plow. Each of these seam engaging surfaces slopes downwardly lengthwise of the seam in a reverse curve from a high point at the forward end of the rib to a low point slightly above the rear end of the rib. With the above described construction the sides or margins of a seam will be turned over against the face of the work by a rolling or molding action which progresses gradually and simultaneously in directions both lengthwise and crosswise of the seam. By maintaining the plow within the seam at all times so that the lower edge of the rib 40 rides continuously along the line of stitches, the sides of the seam will be held in rolled over or spread apart condition up to the very instant when they are engaged by the hammer 14 so that there is no opportunity for them to become displaced before being subjected to the heavy pressure of the hammer. This insures against possibility of irregularity in the appearance of the seam after it is pressed. The gradual curvatures of the seam engaging surfaces of the plow, the absence of any sharp edges or corners which might tend to become embedded in the material operated upon, and the straight line reciprocating movement of the plow which results in alternately accelerating and retarding the seam opening action as the work is being continuously fed past the plow, are all effective to insure against possibility of the work becoming jammed between the plow and the feed roll.

At the rear of the plow, as best shown in Figs. 2 and 3, the transverse curvature of the seam engaging faces is such that the edge portions 46 farthest from the rib 40 project downwardly substantially below the highest points of these faces and when a wide seam is being acted upon, these edge portions of the plow direct the edges of the seam margins downwardly, causing the margins after being spread apart by the plow, to have a cross-sectional contour bulging outwardly from the face of the work between the line of stitching and the outer edges of the seam margins, as shown in Fig. 2. This is desirable inasmuch as it appears that when the margins are thus prepared before reaching the hammer the action of the latter is particularly effective to flatten the seam and to insure permanence in the set thereof.

The invention having been described, what I claim as new and desire to secure by Letters Patent of the United States is:

1. In a machine for performing finishing operations upon boot or shoe parts, a finish-

ing tool movable back and forth along the surface of the work, and a preparing tool slidably supported upon the finishing tool and held continuously in yielding engagement with the work. 70

2. In a seam pressing machine, the combination with a seam pressing member, of means for moving the pressing member toward and from a seam, a seam opening device carried by said pressing member, and means for holding said device constantly in engagement with the work to prevent it from partaking of the movement of the pressing member toward and from the work. 75

3. In a seam pressing machine, in combination, a seam pressing member movable toward and from the work and also movable in a direction to feed the work, and a seam opening device movable with the seam pressing member in its work feeding movements but constructed and arranged to be maintained constantly in substantially uniform engagement with the work. 80 85

4. In a seam pressing machine, in combination, a seam pressing member movable toward and from the work and also movable in a direction to feed the work, a seam opening device movable with the seam pressing member in its work feeding movements but arranged to be independent of the movement of said member toward and from the work, and a spring for maintaining the seam opening device constantly in engagement with the work. 90 95

5. In a seam pressing machine, the combination with a seam pressing member movable toward and from the work and also in another direction to feed the work, of a seam opening device arranged to partake of the feed movement of the pressing member but not of the movements of said member toward and from the work. 100 105

6. In a seam pressing machine, in combination, a support for a piece of work having a seam, a presser member movable toward and from the support for pressing the sides of the seam against the support and back and forth to feed the work over the support, and a seam opening device mounted for back and forth movements in unison with the back and forth movements of the presser member but normally restrained from movement toward or from the work support. 110 115

7. In a seam pressing machine, in combination, a support for a piece of work having a seam therein, a presser member movable toward and from the support for pressing the sides of the seam against the support and back and forth to feed the work over the support, and a seam opening device arranged to partake of the back and forth movements of the presser member but not of the up and down movements thereof. 120 125

8. In a seam pressing machine, in combination, a support for a piece of work having a 130

- seam, a presser member movable toward and from the support for pressing the sides of the seam against the support and back and forth to feed the work over the support, a seam opening device carried by the presser member and movable back and forth in unison therewith, and means for preventing the seam opening device from partaking of the up and down movements of the presser member.
10. 9. In a seam pressing machine, in combination, a support for a piece of work having a seam, a presser member movable toward and from the support for pressing the sides of the seam against the support and back and forth to feed the work over the support, and a seam opening device carried by the presser member, said device being movable back and forth in unison with the presser member and being capable of up and down movement relatively thereto, and means independent of the presser member for limiting the downward movement of the seam opening device.
10. 10. In a seam pressing machine, in combination, a support for a piece of work having a seam, a presser member movable toward and from the support for pressing the sides of the seam against the support and back and forth to feed the work over the support, a seam opening device, yielding means for urging said device toward the work support, and means for limiting the movement of said device under the action of said yielding means.
10. 11. In a seam pressing machine, in combination, a support for a piece of work having a seam, a presser member movable toward and from the support for pressing the sides of the seam against the support and back and forth to feed the work over the support, a seam opening device mounted for back and forth movements in unison with the back and forth movements of the presser member, and a fixed abutment for preventing movement of the seam opening device below a normal vertical position.
10. 12. In a seam pressing machine, in combination, a support for a piece of work having a seam, a presser member movable toward and from the support for pressing the sides of the seam against the support and back and forth to feed the work over the support, a seam opening device mounted for back and forth movements of the presser member, a fixed abutment for preventing movement of the seam opening device below a normal vertical position, and yielding means permitting upward movement of the seam opening device relatively to the presser member.
10. 13. In a seam pressing machine, in combination, a rotary support for a piece of work having a seam, a presser member movable toward and from the support for pressing the sides of the seam against the support and back and forth to feed the work over the support,
- a seam opening plow continuously maintained in position to open the seam and turn the sides back against the face of the work, and means for intermittently moving the presser member and forcing the plow toward the support.
14. In a seam pressing machine, in combination, a roller support for a piece of work having a seam, a hammer for feeding the work from the support and pressing the seam against the support, a plow carried by the hammer for opening the seam, a stationary heating member in sliding engagement with the hammer, means for pressing the plow toward the work, and means on the plow for co-operating with the heating member to position the plow in operative relation with the work.
15. In a seam pressing machine, in combination, a seam pressing hammer having an orbital movement, a seam opening device movable in unison with the hammer and capable of movement relatively to the hammer in two directions, and means tending to prevent movement of said device in any other direction relatively to the hammer.
16. In a seam pressing machine, in combination, a seam support, a member to flatten the seam against the support, a seam opening device carried by said member and yielding urged toward said support, and means independent of the seam flattening member for limiting the movement of the seam opening device.
17. In a seam pressing machine, in combination, a seam support, a movable seam pressing member to flatten the seam against the support, a seam opening device yieldingly mounted on the seam flattening member and continuously maintained in seam opening position, and means for intermittently moving the pressing member and forcing the plow against the seam.
18. In a seam pressing machine, in combination, a seam support, a member to flatten the seam against the support, a seam opening device continuously maintained in seam opening position above the support and shaped simultaneously to open the seam and turn the sides thereof backwardly and downwardly against the face of the work, and means for moving the seam opening device back and forth lengthwise of the seam.
19. In a seam pressing machine, in combination, a seam pressing hammer, a seam opening device movable relatively to the hammer in one direction and in unison with the hammer in another direction, and means for limiting the movement in one direction of the seam pressing member relatively to the hammer.
20. In a seam pressing machine, a seam support, means co-operating with the support to press a seam, a plow movable relatively to the support for opening the seam in advance

of the pressing member, an eccentric for moving the plow, and means constructed and arranged to render the eccentric ineffective to move the plow except in the plane of the work.

21. In a seam pressing machine, a seam opening plow having seam engaging surfaces curving about axes transversely disposed with respect to each other for separating the margins at opposite sides of a seam in a piece of work and for turning the margins over against the face of the work, an oscillatory carrier on which the plow is yieldingly mounted, and means for oscillating said carrier to move the plow lengthwise of the seam.

22. For use in a seam pressing machine, a yieldingly mounted seam opening plow constructed and arranged to present seam engaging surfaces curving gradually both lengthwise and crosswise of a seam which is being opened by the plow, the outer lateral edges of these surfaces at the rear of the plow projecting downwardly substantially below

the highest portions of the rear edges of these faces.

25

23. In a seam pressing machine, a seam opening plow having seam engaging surfaces curving about axes at right angles to each other to separate the margins at opposite sides of a seam, and means for reciprocating the plow while continuously maintaining it substantially in rubbing contact with the stitches of the seam.

24. For use in a seam pressing machine, a seam opening plow having a depending central rib for separating the margins of a seam, and transversely curved seam engaging faces located at opposite sides of the rib and terminating at their outer portions in edges located substantially below the highest points in said faces for rolling the outer edges of the seam margins over toward the face of the work.

In testimony whereof I have signed my name to this specification.

AUGUSTUS D. WILLHAUCK.
